UNITED STATES PATENT OFFICE.

RUDOLPH H. KEAGY, OF CANTON, OHIO.

EMBROIDERY-HOOP.

1,077,987.

Specification of Letters Patent. Patented Nov. 11, 1913.

Application filed September 2, 1910. Serial No. 580,216.

To all whom it may concern:

Be it known that I, RUDOLPH H. KEAGY, a citizen of the United States, residing at Canton, county of Stark, and State of Ohio, 5 have invented certain new and useful Improvements in Embroidery-Hoops, of which the following is a specification.

My invention relates to embroidery hoops and the object of my invention is to provide 10 an improved embroidery hoop formed of sheet metal and which may be manufactured at low cost.

A further object of my invention is to provide an embroidery hoop consisting of 15 two telescopic rings formed with novel clamping surfaces for holding the cloth taut over the inner hoop or ring.

Other objects will appear hereinafter.

With these objects in view my invention 20 consists generally in an embroidery hoop comprising two telescopic rings each made of sheet metal and formed with rolled edges to prevent injury to the cloth. Either the inner or the outer ring is formed with a 25 convex surface whereas the other ring may be either straight walled, curved to conform to the convex surface of the other ring, or oppositely curved as desired. The operative or frictional face of one or both 30 rings is formed to increase the friction on the cloth and hold the same tight while working thereon.

My invention further consists in a pair 35 of telescopic rings adapted to be forced one over the other in the usual manner to tighten and clamp the cloth and the outer ring being split and provided with a suitable clasp or fastening for detachably connecting the ends.

40 My invention further consists in various details of construction and arrangements of parts all as will be fully described herein-after and particularly pointed out in the claim.

45 My invention will be more readily understood by reference to the accompanying drawings forming a part of this specification and in which—

Figure 1 is a perspective view of an embroidery hoop embodying my invention, 50 Fig. 1^a is a modified form of frictional surface, Fig. 2 is a detail section on the line $x-x$ of Fig. 1 illustrating one way in which the ends of the hoops or rings may be 55 cured together, Fig. 3 is a detail vertical

section through the two rings illustrating one form thereof, Fig. 4 is a detail elevation of a portion of the inner hoop shown in Fig. 3, Fig. 5 is a section similar to Fig. 3 illustrating a modified form, Fig. 6 is a 60 section similar to Fig. 3 illustrating a further modification, Fig. 7 is a view similar to Fig. 4 illustrating the inner ring shown in Fig. 6, Figs. 8 to 16 inclusive are similar views illustrating modified forms of my invention, Fig. 17 is a perspective view of a portion of the hoop illustrating a modified form of the means for permanently connecting the ends, and Fig. 18 is a detail view illustrating the form of connection shown in 70 Fig. 17.

Referring now to the drawings 1 indicates the inner ring and 2 the outer ring of an embroidery hoop. These are each formed of sheet metal and are provided with well rounded edges 3 to prevent injury to the cloth or goods which is stretched in the hoop. Either the inner or outer hoop is provided with a convex face, that is a face convexly 75 curved or bulged toward the other hoop. 80

In Figs. 3, 5, 6, 11, 14 and 16 I have illustrated the inner hoop having a convex face and in Figs. 8 and 10 I have illustrated the outer hoop having a convex face. The other hoop or ring may be formed with a straight 85 face or wall as illustrated in Figs. 3, and 6 where the outer ring is so formed and in Fig. 10 where the inner ring is formed with a straight wall, or it may be formed with a concave wall or face conforming to the co-acting face of the other ring as illustrated 90 in Figs. 5, 8, 14 and 16. One or both of the co-acting faces of the rings are formed with means for increasing the frictional contact with the goods. This may consist of a wire 95 mesh secured to the operative face of the ring or the ring itself may be so formed as to provide a frictional face of peculiar form.

In Figs. 3 and 4 I have illustrated an inner ring formed of sheet metal edges or rims 4—4 connected by a strip of wire mesh 5 which is soldered along its edges to the rims 4 making a smooth connection between the parts 4 and 5. In Fig. 5 I have illustrated the outer ring of similar construction, but in this modification the inner ring 6 is formed of one piece of sheet metal and upon the outer surface or operative face thereof is secured as by soldering a strip of 100 105 110

wire gauze or mesh 5'. It is obvious that the outer ring may be constructed in this manner if desired.

In Figs. 6 to 16 inclusive I have illustrated the rings provided with frictional means formed by embossing the metal.

In Figs. 6 and 7 the inner ring is formed with a plurality of diagonally disposed ribs 7 which project outwardly a short distance 10 beyond the normal surface of the ring.

In Figs. 8 and 9 the ribs are V-shaped as at 8 and in Figs. 11 and 12 vertical ribs 9 are provided.

Figs. 15 and 16 illustrate a further modification wherein cross ribs 10 are provided, and in Figs. 13 and 14 short horizontal ribs 11 are formed in the operative face.

In Fig. 10^a further modification is shown, comprising a plurality of small square bosses 12 arranged in parallel horizontal rows and staggered as shown.

Either or both of the rings may be provided with any of the forms of frictional means illustrated and above described.

25 In order to prevent injury to the cloth or goods as the rings are forced one over the other, the embossed portions are formed with smooth rounded edges.

The inner ring has its ends permanently

connected and the outer rings may be also 30 of the same construction if desired. In Figs. 1, 2, 17 and 18 I have illustrated means for permanently connecting the ends. Referring to Figs. 1 and 2 the ends of the rings are overlapped and one end provided with 35 tongues 14 which extend through corresponding apertures 15 in the other end and bent back as shown in the drawings to permanently secure the same together. As shown in Figs. 17 and 18 I provide wire rods or 40 pins 16' which are arranged in the rolled edges 3 and clenched therein as at 16.

Having described my invention what I claim as new and desire to secure by Letters Patent is:

45 An embroidery hoop comprising a pair of telescopic rings each formed of sheet metal, said rings being embossed circumferentially at regular spaced intervals to form smooth incompressible projections on the operative 50 face or faces substantially as described.

In testimony whereof I have signed my name to this specification in the presence of two subscribing witnesses.

RUDOLPH H. KEAGY.
